UNITED STATES PATENT OFFICE.

MORRIS ROSE, OF NEW YORK, N. Y., ASSIGNOR TO BELDING-HALL COMPANY, OF BELDING,
MICHIGAN, A CORPORATION OF MICHIGAN.

DESIGN FOR A REFRIGERATOR.

No. 40,042.

Specification for Design.

Patented June 8, 1909.

Application filed March 6, 1909. Serial No. 481,859. Term of patent 7 years.

To all whom it may concern:

Be it known that I, MORRIS ROSE, a citizen of the United States of America, residing at New York city, New York, have invented a certain new, original, and ornamental Design for a Refrigerator, of which the following is a specification, reference being had to the accompanying drawing, forming part thereof.

The figure is a view in front elevation of a refrigerator, showing my new design.

I claim:

The ornamental design for a refrigerator, as shown.

MORRIS ROSE.
